JAMES M. BROWN, DECEASED, LATE OF PITTSBURGH, PENNSYLVANIA, BY JANE D. BROWN, ADMINISTRATRIX, OF PITTSBURGH, PENNSYLVANIA, ASSIGNOR TO WESTINGHOUSE ELECTRIC AND MANUFACTURING COMPANY, A CORPORATION OF PENNSYLVANIA

SEGREGATED PHASE SYSTEM

Application filed November 1, 1926. Serial No. 145,651.

This invention relates to electrical switching systems and particularly to circuit-interrupter interlocks.

One object of the invention is to provide an electrical interlock between a plurality of remotely disposed circuit interrupters.

Another object of the invention is to provide an electrical interlock between the circuit interrupters controlling a polyphase electrical circuit.

A further object of the invention is to provide an interlock for a plurality of circuit interrupters that is responsive to a condition of dissimilarity in the operating positions of the several circuit interrupters.

In the operation of electrical systems, the circuit interrupters controlling a polyphase electrical circuit are frequently spaced apart a substantial distance. This is especially true where an "isolated phase" arrangement of switching equipment is employed. By reason of the distances separating the circuit interrupters associated with each distributing circuit, it is difficult to mechanically connect the circuit interrupters controlling the several phases of the distributing circuit.

According to the present invention, if any one of the circuit interrupters be opened or closed, when the other circuit interrupters are in dissimilar operating positions, then all the circuit interrupters controlling each circuit will be tripped to their open positions.

The single figure of the accompanying drawing, is a diagrammatic view of circuits and apparatus embodying the invention.

The invention comprises, in general, a plurality of circuit interrupters 1, 2 and 3 that control the A, B and C phases of an electrical circuit, respectively, having the usual overload tripping mechanisms 4 and an auxiliary tripping mechanism 5 that is responsive to conditions of dissimilarity between the operating positions of any two of the circuit interrupters 1, 2 and 3.

The circuit interrupters 1, 2 and 3, may be of any desired type that may be simultaneously closed, comprising a tripping toggle 6, as the details thereof form no part of the present invention.

Each of the tripping mechanisms 4 com-

prises a current transformer 7 that energizes a solenoid 8 for actuating an armature member 9 that is connected, by a rod 11, to the toggle 6 of the associated circuit interrupter 1, 2 or 3.

Each of the auxiliary tripping mechanisms 5 comprises a solenoid 12 that actuates an armature 13, mounted on the rod 11, and a two-position pilot switch 14, connected by a link 15, a bell crank 16 and a lever 17 that is pivoted, as at 18, to the associated circuit interrupter 1, 2 or 3. Lost-motion connections are provided between each lever 17, bell crank 16 and circuit interrupters 1, 2 or 3, in order to compensate for the circular movement of the ends of the lever 17.

The pilot switches 14 bridge a plurality of contact members 19 and 21 when in their upper circuit-closing positions, and bridge a plurality of stationary contact members 22 and 23 when in their lower circuit closing positions.

The several stationary contact members 19 are connected to the positive conductor of a supply circuit 24. The stationary members 21 and 22 are all connected to each other by a looped conductor 25. The several stationary contact members 23 are connected to a common conductor 26 that is connected through the several solenoids 12, in parallel circuit, to the negative conductor of the supply circuit 24.

Electrical operating mechanisms 26, are attached to each of the circuit interrupters and are connected in parallel in the circuit 24. A control switch 28 is provided in one side of the circuit 24 and is employed to close the circuit interrupters simultaneously.

When the circuit interrupters 1, 2 and 3 are all their open positions, as shown in the accompanying drawing, the several pilot switches 14 are in their lower contact making positions, and the looped conductor 25 is connected to the negative conductor of the supply circuit 24 through the several stationary contact members 22, 23 and the solenoids 12, in parallel circuit. At the same time, the positive conductor of the supply circuit 24 is electrically separated from the looped conductor 25 between the several pairs

of contact members 19 and 21. If any one of the circuit interrupters 1, 2 or 3 is moved to its closed position, its pilot switch 14, is moved to close a circuit between the stationary contact members 19 and 21, thereby energizing the looped conductor 25 and the several solenoids 12. Upon energization of the several solenoids 12, their armature members 13 are attracted to trip the toggles 6, thereby opening all the circuit interrupters 1, 2 and/or 3 that are in their closed positions to move them to their open-circuit positions.

When the several circuit interrupters 1, 2 and 3 are in their closed positions, the several pilot switches 14 are in their upper circuit-closing positions, thereby completing circuits through the stationary contact members 19 and 21 from the positive conductor of the supply circuit 24 to the looped conductor 25. However, the circuit between the several stationary contact members 22 and 23, is broken. Should any one of the circuit interrupters 1, 2 and 3, be tripped to its open position, by the operation of the overload tripping mechanisms 4, or by reason of failure of the mechanical parts of the circuit interrupter itself, then the pilot switch 14 associated with that circuit interrupter, is turned to complete a circuit between the stationary contact members 22 and 23. The looped conductor 25 is thereby connected to the conductor 26 and the several parallel connected solenoids 12, with the result that the toggle mechanisms 6 of the circuit interrupters 1, 2 and 3, are energized to trip the circuit interrupters remaining in their circuit-closing positions.

Accordingly, there has been provided an interlock for controlling the circuit interrupters associated with the several phases of an alternating current circuit that is responsive to a condition of dissimilarity between the operating positions of the several circuit interrupters.

It is to be understood that such changes may be made in the structural details, arrangement and disposition of the component parts of the invention as shall be within the scope of the appended claims.

Claims:

1. The combination with a polyphase circuit, a circuit interrupter having an open and a closed position for each phase, and tripping means for said circuit interrupters responsive to conditions of overload, of auxiliary means for the several circuit interrupters adapted to trip them to their open positions whenever any one of the circuit interrupters occupies a different position from that of the other said circuit interrupters, and means for deenergizing said auxiliary means during the time the circuit interrupters occupy like positions.

2. The combination with a polyphase circuit, a circuit interrupter having an open

and a closed position for each phase and tripping means for said circuit interrupters responsive to conditions of overload, of auxiliary tripping means for the circuit interrupter only when any two of the plurality of circuit interrupters occupy different said positions.

3. The combination with a polyphase circuit, a circuit interrupter having an open and a closed position for each phase and tripping means for said circuit interrupters responsive to conditions of overload, of auxiliary tripping means associated with the circuit interrupters adapted to cause the circuit interrupters in closed position to move to their open positions whenever any of them are in open positions and means for deenergizing said auxiliary means when the circuit interrupters occupy like positions.

4. The combination with a polyphase circuit, circuit interrupter having an open and a closed position for each phase and tripping means for said circuit interrupters responsive to conditions of overload, of auxiliary tripping means associated with the circuit interrupter comprising a pilot switch that is adapted to cause all of the circuit interrupters in closed position to move to their open positions whenever any one of them occupy the open position and to deenergize said auxiliary means thereafter.

5. The combination with a polyphase circuit, of a circuit interrupter having a closed and open position for each phase, a tripping mechanism for the circuit interrupters, and a switch completing a circuit to the tripping mechanism actuated in response to the dissimilarity of position of any two said circuit interrupters and means associated with the switch for deenergizing the tripping mechanism when the circuit interrupters occupy like positions.

6. In a circuit-interrupter system, a plurality of associated circuit interrupters provided with means for moving them to like operative positions, a tripping means associated with each circuit interrupter, and means for energizing the several tripping means only when two of the circuit interrupters occupy different operative positions.

7. In a circuit-interrupter system, a plurality of associated circuit interrupters provided with means for moving them to their closed-circuit positions, tripping means associated with each circuit interrupter, and means for energizing the several circuit interrupters to move to their open positions whenever any two of the circuit interrupters occupy different positions and for deenergizing said tripping means thereafter.

8. The combination with a polyphase circuit, of a circuit interrupter having a closed and an open position for each phase, tripping mechanism for the circuit interrupters,

and energizing means for the tripping mechanism actuated in response to a condition of dissimilarity of positions between any two circuit interrupters, the said tripping mechanism being energized only when the circuit interrupters occupy unlike positions.

9. The combination with a plurality of associated circuit interrupters normally occupying like positions, of tripping means for the said circuit interrupters deenergized when the circuit interrupters occupy like closed or open positions, and interlock switching means for effecting the energization of said tripping means only in response to conditions of non-conformity of positions between any two circuit interrupters.

10. The combination with a plurality of associated circuit interrupters normally occupying like positions, of tripping means associated with each circuit interrupter in parallel-circuit relation, and interlock switching means responsive only to conditions of dissimilarity of positions of the circuit interrupters for completing a circuit to said tripping means.

In testimony whereof, I have hereunto subscribed my name this 27th day of October, 1926.
